Primary Examiner—Charles A Rademaker
(74) Attorney, Agent, or Firm—Tillman Wright, PLLC; Chad D. Tillman; James D. Wright(57) CLAIM

The ornamental design for a cover for serving tray, as shown and described.

DESCRIPTION

FIG. 1 is a perspective view of a cover for a serving tray showing my new design; and,

FIG. 2 is a top plan view thereof.

The broken lines shown in the drawings are included for the purpose of illustrating structural environment and form no part of the claimed design.
